UNITED STATES PATENT OFFICE.

JOSIAH COOKERLEY, OF SOUTH MILFORD, INDIANA.

WRENCH.

1,188,735.

Specification of Letters Patent. Patented June 27, 1916.

Application filed November 13, 1914. Serial No. 871,936.

To all whom it may concern:

Be it known that I, JOSIAH COOKERLEY, a citizen of the United States, residing at South Milford, in the county of Lagrange and State of Indiana, have invented a new and useful Wrench, of which the following is a specification.

The present invention relates to improvements in wrenches, one object of the invention, being the provision of a type of wrench, in which the nut engaging member or jaw is mounted swingingly, so that the same may be disposed and locked at any desired angularity relative to the operating handle, to thus accommodate the same for use in various positions.

A further object of the present invention, is the provision of a simple, inexpensive and durable wrench of this character, which is thoroughly efficient and practical in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the complete wrench. Fig. 2 is a top plan view thereof. Fig. 3 is a section taken on line 3—3 of Fig. 2. Fig. 4 is a section taken on line 4—4 of Fig. 1.

Referring to the drawings, the numeral 1 designates the connecting plate or portion of the main operating handle, said handle being provided with the two parallel portions 2 which constitute a casing having a longitudinal groove or channel, while disposed at one end of this channeled handle, are the two portions 3 whose ends are rounded and which are apertured for the reception of the removable bolt or pin 4 which in turn mounts for swinging movement, the substantially circular ear 5 of the movable jaw 6. This pin 4 is so constructed

as to be readily adjusted and removed so that various sized jaws 6 may be employed with a single structure.

Mounted for swinging movement upon the pin 6' is the pivoted or swinging handle 7 which is normally extended to assume the position as shown in Figs. 1 and 3, by means of the spring 8, which is attached at one end to the handle 7 and has its free end 9 curved and engaging the under side of the plate 1 of the other handle.

The curved end 10 of the member 7 is formed eccentrically to the pin 6', so that when the handle 7 is gripped and moved toward the main handle consisting of the portions 1 and 2, the end 10 will engage the circular ear 5 of the jaw 6 and thus lock the jaw against movement. Before such movement of the handle 7, the jaw 6 may be positioned at any desired position, so that a portion of the circular ear 5 will be presented to the eccentric surface 10.

It will thus be seen that it is merely necessary to adjust the jaw 6 to the desired angularity and to actuate the handle 7 toward the main handle so that the concentric periphery of the ear 5 will be engaged with the eccentric surface 10, thus locking the parts immovably.

Upon the release of the handle 7, the spring 8 will return the parts to the position as shown so that the surface 10 will be moved out of engagement to release the circular portion 5.

Where found desirable or necessary, the surfaces 5 and 10, or either one of them, may be roughened to insure against slipping when gripping a nut.

What is claimed is:

The combination with a longitudinally channeled handle having an enlarged bifurcated end, of a nut engaging member, an ear extending therefrom and pivotally mounted within the bifurcated portion of the handle, said ear being substantially circular and concentric with its pivot, a combined handle and clamping lever pivotally mounted within the channeled handle and

having a clamping face eccentrically disposed relative to the pivot of said lever, said face being shiftable into engagement with the periphery of the ear, said periphery and eccentric face being smooth and continuous.

In testimony that I claim the foregoing

as my own, I have hereto affixed my signature in the presence of two witnesses.

JOSIAH COOKERLEY.
